UNITED STATES PATENT OFFICE

AMOS K. ERSLAND, OF MANHATTAN BEACH, CALIFORNIA

WRENCH

Application filed April 28, 1930. Serial No. 448,045.

My invention relates to wrenches of the quick adjustment type which have a pivoted and traveling outer jaw to render the wrench applicable to pipes as well as nuts of different sizes.

It is a purpose of my invention to provide a wrench of the above described character which has a pawl for locking the shank of the outer jaw in any longitudinal position of adjustment and in such manner that the outer jaw is free to occupy any divergent position with respect to the inner jaw without rendering the pawl ineffective to lock the shank, the pawl including a plurality of integrally spaced teeth all of which remain in mesh with the teeth of a rack on the shank irrespective of the divergent position of the outer jaw, and by which teeth a fine adjustment of the outer jaw can be effected.

It is also a purpose of my invention to provide a latching device manually operable to cause the pawl and the rack of the outer jaw shank to engage and disengage each other to lock and release the outer jaw, and when the two are disengaged permitting quick longitudinal adjustment of the shank to attain any desired adjustment of the outer jaw with respect to the inner jaw.

I will describe only one form of wrench embodying my invention, and will then point out the novel features thereof in claims.

In the accompanying drawing:

Fig. 1 is a view showing in longitudinal section one form of wrench embodying my invention and wherein the outer jaw shank is in released position with respect to the pawl to allow the quick adjustment of the outer jaw.

Fig. 2 is a view similar to Fig. 1 showing the outer jaw shank engaged and locked by the pawl.

Fig. 3 is a view similar to Fig. 2 illustrating the permissible transverse movement of the outer jaw shank when locked by the pawl to allow the outer jaw to occupy a divergent position with respect to the inner jaw.

Fig. 4 is a fragmentary view showing the wrench in rear elevation and with the latching device in the same position as illustrated in Fig. 1.

Fig. 5 is a transverse sectional view taken on the line 5—5 of Fig. 1.

Figs. 6 and 7 are detail perspective views of the spring and latch member, respectively, of the wrench shown in the preceding views. 55

In carrying out my invention, I provide a handle H including an elongated shank 15, and a body at one end of the shank having parallel portions 16 connected by a back portion 17, the parallel portions exceeding in width that of the shank to provide a mounting for and accommodate other parts of the wrench. 60

By means of rivets 18 and 19 the shank 20 for an inner jaw 21, is fixedly secured between the parallel portions 16, it being understood that the jaw 21 is formed integral with the shank 20. The inner edge of the shank 20 is shaped to provide divergent surfaces 20^a and 20^b to form a pocket in which a pawl P is adapted to be received, the surface 20^b terminating short of the jaw 21 to provide an intervening surface 20^c against which the upper end of the pawl P is adapted to abut. It is important to note that this surface 20^c is offset with respect to the adjacent end of the jaw 21 in order that when the upper end of the pawl engages such surface it will be disposed substantially flush with the end of the jaw. This is for the purpose of permitting unrestrained longitudinal movement of the outer jaw shank when the pawl is ineffective to lock the outer jaw shank in a longitudinal position of adjustment. 75

The outer jaw, indicated at 22, is provided with a shank 23 formed on one longitudinal surface with a rack 24 which is adapted to engage teeth 25 of the pawl P to secure the shank 23 in a longitudinal position of adjustment and to thereby lock the jaw 22 in a fixed 90 position of adjustment with respect to the inner jaw 21. The inner end of the shank 23 is provided with a detent 26 which is adapted to abut the inner end of the pawl P to confine the shank against complete withdrawal from the handle. 95

The pawl P is fulcrumed to move about a pin 27 which extends through the parallel portions 16 of the handle, and that face of the pawl confronting the inner edge of the shank 100

20 is shaped to correspond to the shape of such shank edge. This is for the purpose of permitting the necessary rocking movement of the pawl to allow the shank 23 to move transversely and to the end of permitting the outer jaw 22 to occupy any required divergent position with respect to the inner jaw 21. The teeth 25 extend only from the lower end of the pawl to a point opposite that of the fulcrum pin 27, the remainder of the pawl face being smooth, and engageable by the rack when the upper end of the pawl abuts the surface 20^a and the outer jaw is rocked to the left as viewed in Figure 1, from which it will be clear that upon further rocking movements of the jaw to the left, the jaw will pivot about the upper end of the pawl and free the rack from the pawl teeth, thus permitting longitudinal movement of the outer jaw.

20 By the provision of a latching device, the shank 23 can be urged transversely to the left, as when viewed in Fig. 2, causing the rack 24 to engage the pawl teeth 25, and yet allow the shank to swing transversely to the left and about the fulcrum pin 27 as a center to permit the outer jaw to occupy a divergent position with respect to the inner jaw. However, this latching device is capable of being manipulated manually to occupy either of two extreme positions in which it is active and passive, respectively, to engage and disengage the shank 23 so that the latter will be locked or released, respectively, by the pawl P. This latching device comprises a member 29 disposed within a slot 30 in the back portion 17 of the wrench handle, and to the inner side of which a bowed spring 28 is secured by means of rivets 31 and in such manner that the spring projects beyond the opposite ends of the body 29, as illustrated in Fig. 2. At its upper end the body 29 is formed with an offset wedge shaped key 32 provided at its free extremity with a detent 33, while at its lower end the body is provided with an offset extension 34 having at its free extremity a detent 35. The key 32 and the extension 34 are reversely disposed with respect to the body 29 so that when the body is in position within the slot 30, the key 32 is positioned for movement between the shank 23 and the back portion 17 of the handle, while the extension 34 is positioned to move within the slot 30 as well as to the outer side of the portion 17. The spring 28 is secured to the body 29 so as to have a portion 28^a disposed substantially in spaced parallelism with the extension 34 in order that it may coact with the latter to confine the latch body 29 against complete displacement from the slot 30.

60 The outer surface of the body 29 is dished as indicated at 29^a to provide a seat for the finger by which the body can be moved upwardly from the position shown in Fig. 1 to that shown in Fig. 2. The body is also provided with a pair of wings 36 which are

adapted to be gripped for moving the body downwardly from the position shown in Fig. 2 to that shown in Fig. 1. Thus the body 29 is capable of occupying two extreme positions. In the first extreme position, as illustrated in Fig. 1, the key 32 is disposed within the slot 30 and removed from between the shank 23 and the handle portions 17. In this position of the key, the detent 33 engages the upper end wall of the slot 30 to confine the key against complete displacement from the slot. At the lower end of the body 29, the spring portion 28^a engages the inner side of the handle portion 17 to confine the body 29 against displacement from the slot. In this position of the latch body, the key 32 being withdrawn from between the shank and the handle, permits the spring 28 to occupy a normal position in which it is still effective to urge the shank 23 to cause the rack 24 to engage the pawl teeth 25 but to lesser degree so that by gripping the outer jaw 22 and moving it to the right, as when viewed in Fig. 1, the rack can be moved free of the pawl. As a consequence, the shank 23 is free to be moved longitudinally to effect a quick adjustment of the outer jaw 22. With the latch member in the position shown in Fig. 2, the key 32 is projected between the shank 23 and the handle portion 17 thereby transversely shifting the shank 23 to the left to cause the rack 24 to more firmly engage the pawl teeth 25. In this position of the body 29 the detent 35 engages the lower end wall of the slot 30 to confine the extension 34 against movement inwardly through the slot 30.

Thus with the shank 23 shifted so that the rack 24 engages the pawl teeth 25, the shank is locked against longitudinal movement, and consequently the jaw 22 is secured in a fixed position of adjustment with respect to the inner jaw 21. However, the jaw 22 is not restrained against a movement to occupy divergent position with respect to the jaw 21 for the shank 23 can move transversely about the fulcrum pin 27 as a center rocking on a projection 32^a of the key 32 upon which the shank bears. Such a movement of the shank 23 does not cause the rack 24 to disengage the pawl teeth 25, because of the location of the bearing projection 32^a, in respect to the fulcrum 27. Thus the outer jaw 22 is capable of movement to occupy any divergent position without disturbing its position of adjustment with respect to the jaw 21.

As will be clear from a consideration of Figs. 2 and 3, that portion of the spring 28 above the key 32 flexes in response to transverse or rocking movement of the shank 23 thus placing the spring under tension which functions to return the shank to a vertical position once the pipe or other element being gripped by the wrench is removed from be-

tween the jaws. In order that the shank 23 as well as the spring 28 may occupy a maximum angular position as illustrated in Fig. 3, the upper end of the handle portion 17 is 5 beveled as indicated at 37.

In practice, the key 32 when in the position shown in Fig. 1 permits adjustment of the jaw 22 to receive and grip a pipe or other piece of work between the jaws, and once 10 proper adjustment has been attained, the key is moved to the position shown in Fig. 2 thereby locking the jaw in the position to which it has been adjusted. To rotate the pipe, the handle H is oscillated in the usual 15 manner, the shank 23 swinging about the pin 27 as a center when the handle is moved in one direction in order to permit the jaw 22 to assume a divergent position with respect to the jaw 21. However, when the handle is 20 moved in the opposite direction the spring 28 functions to return the jaw 22 to a parallel position with respect to the jaw 21 so that the pipe is momentarily released to allow such movement of the handle, and following 25 which, the handle may be moved in the other direction to cause the jaw 22 to again occupy divergent position in which the pipe is wedged between the jaws and the turning thereof effected as a consequence.

30 Although I have herein shown and described only one form of wrench embodying my invention, it is to be understood that various changes and modifications may be made therein without departing from the 35 spirit of the invention and the spirit and scope of the appended claims.

I claim:

1. A wrench comprising a handle, an inner jaw fixed on the handle, an outer jaw having a 40 shank movable longitudinally to effect adjustment of the outer jaw with respect to the inner jaw and transversely to cause the outer jaw to occupy a divergent position with respect to the inner jaw, a rack on said shank, a pawl 45 fulcrumed in the handle, a member movable on the handle to occupy either of two extreme positions, a spring secured to the member and engaging said shank for yieldably urging the latter transversely to cause the outer jaw to 50 occupy a parallel position with respect to the inner jaw, and a key carried by the member so that in one extreme position of the latter it is interposed between the shank and the handle to move the shank to a position in 55 which the rack engages the pawl, and in the other extreme position of the member to be withdrawn from between the shank and handle to allow the rack to be moved out of engagement with the pawl.
- 60 2. A wrench as embodied in claim 1 wherein the member is provided with an extension and the spring is secured to the member so as to coact with the extension in providing a means for confining the member against 65 transverse displacement from the handle.

3. A wrench as embodied in claim 1 wherein in the member is dished to provide a seat for the finger for moving the member from one extreme position, and with wings adapted to be gripped for moving the member to the 70 other extreme position.

4. A wrench comprising a handle, an inner jaw fixed to the handle, an outer jaw having a shank movable longitudinally and transversely in the handle and provided with a 75 rack, a pawl fulcrumed in the handle, means in the handle engaging the shank and acting to yieldingly urge the rack into engagement with the pawl, and means manually operable to move the shank transversely and latch its rack in engagement with the pawl.

5. A wrench comprising a handle, an inner jaw fixed to the handle, an outer jaw having a shank movable longitudinally and transversely in the handle and provided with a 85 rack, a pawl fulcrumed in the handle, yieldable means engaging the shank for normally acting to move the rack into engagement with the pawl, a detent on the shank positioned to engage the pawl for preventing complete 90 withdrawal of the shank from the handle, and manually operable means mounted on the handle and movable to latch the rack in engagement with the pawl.

6. A wrench comprising a handle having 95 an inner jaw, an outer jaw having a shank provided with a rack and mounted in the handle for movement longitudinally and transversely of the latter, a pawl mounted on the handle, means engaging the shank to 100 urge the rack into engagement with the pawl, and locking means co-acting with the last means and handle to lock the rack in engagement with the pawl.

7. A wrench comprising a handle having 105 an inner jaw, an outer jaw having a shank provided with a rack and mounted in the handle for movement longitudinally and transversely of the latter, a pawl fulcrumed in the handle, means for urging the shank to engage its rack with the pawl, and means for locking the outer jaw against disengagement of its rack from the pawl, while rendering the outer jaw free to rock with the pawl about the axis of the latter.
